UNITED STATES PATENT OFFICE.

ARTHUR G. PALMER, OF HASTINGS-UPON-HUDSON, NEW YORK.

FAVOR AND SNAPPING MOTTO.

Application filed May 22, 1920. Serial No. 383,583.

To all whom it may concern:

Be it known that I, ARTHUR G. PALMER, a citizen of the United States of America, residing at Hastings-upon-Hudson, West-
5 chester County, State of New York, have invented new and useful Improvements in Favors and Snapping Mottoes, of which the following is a specification.

This invention relates to favors used at 10 dinners and on other occasions and has special reference to that class of favors which are pulled apart by grasping their ends. The pulling apart of the favors as described usually has the effect of producing a motto 15 or a snapping or explosive noise.

The present invention contemplates manipulation of a favor in the manner as indicated but the device is so constructed and arranged that such manipulation will cause 20 an object, which may vary greatly in character and significance, to unexpectedly appear whereby the pleasure derived from the favor is greatly increased.

Other and ancillary objects of the invention will appear hereinafter.

In the accompanying drawings which illustrate the invention;

Fig. 1 is a perspective view of a structure embodying the invention;

30 Fig. 2 is a longitudinal, central section; Fig. 3 is a section on the line 3—3 of Fig. 2;

Fig. 4 is a section on the line 4—4 of Fig. 2 but modified as will hereinafter appear; and with certain parts omitted.

Fig. 5 is a central, longitudinal section of one end of a modified structure with the outer covering removed; and

40 Figs. 6 to 13 inclusive show the blank parts from which the device is made as will hereinafter more fully appear.

Referring to the drawings, the apparatus 45 comprises a cylindrical body portion 1 formed by taking a sheet of stiff paper or cardboard, as shown in Fig. 6, and rolling it into the form of a cylinder. In the sheet 1 are formed two holes 2 and 3 by cutting away a rectangular section of the material except at an edge so that the tongues 4 and 50 5 may be moved out of the plane of the sheet to form the holes and in the completed device may be bent down and gummed to the sheet 1, leaving the holes 2 and 3 open and reinforcing the bottom of the cylinder when a spring is attached. The sheet as thus constructed is then rolled into the form of a

cylinder as shown clearly in Fig. 3 with the holes 2 and 3 in registry so that the opening 6 is formed in the cylindrical body. About this cylindrical body is then wrapped a thinner sheet of flexible paper 7 as shown in Fig. 8, so that the opening 8 formed by cutting and turning back the triangular shaped flaps 9 is in registry with the hole 6. The overlapping edges of the sheet as shown in Fig. 8 are then gummed together and so hold the body in permanent cylindrical form. The triangular flaps 9 are turned inwardly around the edges of the hole 6 and gummed to the interior of the body 1. This prevents the presentation of any raw edges of the thin paper at the margin of the hole so that danger of tearing of this thinner enclosing paper is avoided.

In the side of the cylindrical body 1 opposite the hole 6 is secured by gumming or otherwise, a strip of pasteboard 10 furnishing the base upon which devices upon the interior of the body may be mounted. The blank constituting this strip is shown in plan in Fig. 7 having slits 11 for a purpose as will be hereinafter referred to. At each end of the cylindrical body 1 is arranged a snapping device. That at one end comprises the strip 12 of pasteboard having its ends overlapping the pasteboard strip 13 which is secured by gluing or otherwise to the strip 10. The overlapping ends of the strips 12 and 13 are provided with a snapping composition, or explosive which is adapted to be set off when the members 12 and 13 are drawn apart by pulling upon the member 12, these overlapping ends being covered with a wrapping 14 as shown. The structure and treatment of the overlapping ends with a snapping compound or explosive so that the snap or explosion occurs upon the drawing apart of the members, is well understood in the art and need not be described further here.

At the other end of the body a similar arrangement is provided comprising the pasteboard strip 15 secured to the strip 10, the explosive or snapper at 16 and the other member 17 having its end overlapping that of the strip 15 as previously described in connection with a similar device at the other end of the body.

Fig. 9 shows a structure which may be employed at each end of the favor 8 comprising two strips with the snapper in the middle as above referred to. A flat steel

spring device comprising a flat steel spring 18 and the weight 19 at one end, has the end opposite the weight inserted through the slots 11 in the strip 10 and then has its weighted and free end bent into the position as shown in Fig. 2. A loop of paper 20 is passed over the spring and is secured by gumming or otherwise to the strip 10 and acts to hold the weighted end of the spring in retracted position as shown. The blank forming this strip of paper is shown in Fig. 12.

Secured to the weighted end of the spring may be any desired figure such as the conventional illustration of "Uncle Sam" as indicated, a flag, or other desired miniature figure or emblem, or if a gift more substantial is desired, stick pins or articles of jewelry may be likewise secured to the weighted or free end of the spring.

Extending through the cylindrical body 1 is a fine wire 21 secured to the outer member 12 at one end by being coiled about it or in other suitable ways and at the other end is similarly secured to the strip 17. This wire is looped about the paper strip 20 so that as the members 12 and 17 are drawn apart the paper band 20 is severed and the end of the spring held thereby released. The result is that the figure, emblem or other article carried by the spring is caused to move quickly through the opening 6 and be exposed at the side of the cylinder.

In manufacturing this device, after the spring 18 has been inserted in the slots 11 of the strip 10, the figure or gift is secured to the spring 18 which is bent into retracted position and secured by the paper strip 20 which passes over the spring and has its ends glued to the strip 10. The snapping devices as shown in Fig. 9 are then glued to the strip 10, as shown in Fig. 2 and the wire 21 is looped about the paper strip 20 and has its ends wrapped about the snapper members 12 and 17 as shown in Fig. 2. The article thus assembled may be inserted endwise into the cylinder and secured in position by gumming or gluing the strip 10 to the cylinder 1. The crape paper being then applied, the article will be complete.

With the parts arranged as shown in Fig. 2, a sheet of colored crape paper may be wrapped about the cylinder and project beyond its ends to a considerable extent. Another sheet of crape paper of a different color may be then wrapped about the first and still another sheet of paper of a different color may be wrapped about the last. The paper may then be gathered at the ends of the cylinder by tying strings or ribbons as 22 about the crape paper which extends beyond the ends of the cylinder 1 so as to close the end of the cylinder. That portion of the crape paper extending beyond the point where it is tied may be slit to form tassel-like struc-

tures as 23 and 24 and where the layers of crape paper are of different colors as described these tassels will be composed of strips of different colors so as to give a very pleasing appearance. Thus, the device may have three layers of crape paper, the layers being of red, white and blue respectively. The tassels will then be composed of red, white and blue filaments or strips. Where the crape paper overlies the opening 6 it may be slit or shredded so that the spring and its carried parts may easily force its way therethrough and where the layers of crape paper are of different colors as described, the intermingling of the shreds will form a pleasing ornamentation and back ground for a picture or appropriate decoration upon the side of the favor.

The members 12 and 17 extend out into the tassels 23 and 24 so that upon grasping the tassles and ends 12 and 17 and pulling them in opposite directions along the axis of the device, the release of the spring and operation of the snappers or explosives as before referred to will be effected.

It will now appear that with the device constructed as described, if the tassels and ends 12 and 13 at the ends of the device are grasped and pulled in opposite directions, the members 12 and 13 will be separated operating the snapper 14 and the members 15 and 17 will be separated operating the snapper 16, while the separation of the members 12 and 17 will cause the paper loop 20 to be severed, thereby releasing the steel spring, the free and weighted end of which will fly upwardly bringing whatever is carried by it (in this case the conventional figure of Uncle Sam) into a position substantially at right angles to the cylinder as indicated by the dotted lines in Figs. 2 and 3.

In some instances it may be desired to place a covering or lid over the opening 6 in which case a blank as shown in Fig. 10 may be employed. This blank comprises a relatively stiff piece 25 of paper or similar material, the stiffness and thickness of which may be substantially that of the material of the cylinder 1 and to this piece 25 may be gummed a separate piece of thinner paper 26 to form a hinge. The lid may then be secured to the cylinder so as to cover the opening 6 when closed, by gumming the free edge of the paper 26 to the side of the cylinder as shown in Fig. 4. Normally the lid would be closed as shown but would be thrown open by the flying of the spring and its figure into vertical position as before referred to the cylinder with the lid is covered with the colored crepe paper as before described.

It may enhance the amusement derived from the device to place a whistle or similar device within the cylinder 1 and to this end a blank as shown in Fig. 13 may be turned about an axis when it will form a cone-

shaped member as shown at 27 in Fig. 5. In the smaller end of this member may be placed a whistle 28 which will be sounded if one blows in the end of the cylinder. A combination favor and musical toy is thus formed.

While the invention has been illustrated in what is considered its best application it may have other embodiments without departing from its spirit and is not therefore, limited to the structure shown in the drawings.

What I claim is:

1. In a favor or snapping motto, the combination with a hollow cylinder of a lateral opening therein, a spring mounted device within said cylinder adapted to be projected through said opening when released, means for restraining said device, means for controlling said restraining means and a cover for said opening.

2. In a favor or snapping motto, the combination with a hollow cylinder, of a lateral opening therein, a spring mounted device within said cylinder adapted to be projected through said opening when released, means for restraining said device, means for controlling said restraining means and a hinged cover for said opening.

3. In a favor or snapping motto, the combination with a hollow cylinder, having a lateral opening, of a device within said cylinder movable through said opening and a layer of paper wrapped about said cylinder and over said opening, said layer of paper extending beyond the ends of said cylinder and means for controlling said device extending beyond the ends of said cylinder and within said paper, said paper being slit 40 into strips or filaments and gathered together to close the ends of said cylinder.

4. In a favor or snapping motto, the combination with a hollow cylinder, of a lateral opening therein, a spring mounted device within said cylinder adapted to be projected through said opening when released, means for restraining said device, means for controlling said restraining means and a

cover for said opening and a snapper operated by said controlling means.

5. In a favor or snapping motto, the combination with a hollow cylinder having a lateral opening, a device within said cylinder and movable through said opening and a layer of paper wrapped about said cylinder and over said opening, said layer of paper extending beyond the ends of said cylinder and means for controlling said device extending beyond the ends of said cylinder and within said paper, said paper being shreadded over said opening.

6. In a favor or snapping motto, the combination with a hollow cylinder having a lateral opening, of a device within said cylinder movable through said opening and a plurality of layers of paper of different colors wrapped about said cylinder and over said opening, said layers of paper extending beyond the ends of said cylinder, means for controlling said device extending beyond the ends of said cylinder and within said paper, portions of the paper layers extending beyond the ends of said cylinder being slit into strips or filaments and gathered together to close the ends of said cylinder.

7. In a favor or snapping motto, the combination with a hollow cylinder having a lateral opening, of a spring mounted device moving through said opening, a paper strip restraining said device, a snapper, operating means therefor, a wire operatively related to said operating means and adapted to sever said paper strip when said snapper is operated, a layer of paper surrounding said cylinder and extending over said opening, said paper extending beyond the ends of said cylinder and being slit into strips or filaments beyond the ends of said cylinder and means for gathering the paper of said layer together to close the ends of said cylinder, said snapper operating means extending beyond the ends of said cylinder.

In testimony whereof I have signed this specification this 30th day of March, 1920.

ARTHUR G. PALMER.
